(57) **CLAIM**

We claim the ornamental design for a riflescope, as shown and described.

DESCRIPTION

FIG. 1 is a side perspective view of the riflescope of our new design;

FIG. 2 is a right side elevation view of the riflescope of FIG. 1;

FIG. 3 is a left side elevation view of the riflescope of FIG. 1;

FIG. 4 is a top view of the riflescope of FIG. 1;

FIG. 5 is a bottom view of the riflescope of FIG. 1;

FIG. 6 is a rear elevation view of the riflescope of FIG. 1; and,

FIG. 7 is a front elevation view of the riflescope of FIG. 1. The broken lines in FIGS. 1-7 are for illustrative purposes only to show the placement of the claimed design and form no part of the claimed design.
